(57) **CLAIM**

The ornamental design for a charge coupler handle, as shown and described.

DESCRIPTION

FIG. 1 is a perspective view of a left side of a charge coupler handle showing our new design;

FIG. 2 is a perspective view of a right side of the charge coupler handle thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken line portion of the figure drawings is included for the purpose of illustrating environment and forms no part of the claimed design.
